Primary Examiner — Mark Goodwin(74) *Attorney, Agent, or Firm* — I. Morley Drucker; Fulwider Patton LLP(57) **CLAIM**

The ornamental design for a blower impeller, as shown and described.

DESCRIPTION

FIG. 1 is a top plan view of a blower impeller showing my new design;

FIG. 2 is a side elevational view thereof;

FIG. 3 is a top perspective view thereof; and,

FIG. 4 is a bottom plan view thereof.

The broken lines shown in the drawings represent unclaimed portions of the blower impeller and form no part of the claimed design.
